UNITED STATES PATENT OFFICE.

AXEL R. GUSTAFSON, OF CHICAGO, ILLINOIS, ASSIGNOR TO WALTER J. CONLON, OF OAK PARK, ILLINOIS.

IRONING MACHINE.

Application filed January 17, 1919. Serial No. 271,634.

To all whom it may concern:

Be it known that I, AXEL R. GUSTAFSON, a citizen of the United States, residing at Chicago, in the county of Cook and State of Illinois, have invented certain new and useful Improvements in Ironing Machines, of which the following is a specification.

This invention relates to improvements in ironing machines and more particularly to ironing machines adapted particularly for family use. One object is to provide a machine of this type that is of simple construction, cheap to manufacture and efficient in operation. A further object is to provide a machine that can be operated without danger of bodily injury to the operator and that, due to its simplicity of construction, can be operated readily by a person having little experience with machines of this class. The machine is so constructed and assembled that it can be used to iron the most delicate fabric without danger of damage to the same and at the same time it will, with equal satisfaction, iron coarse or heavy fabrics in a thoroughly efficient manner.

With the foregoing and other objects in view the invention consists in the combination and arrangement of parts to be herein-after fully described, pointed out in the appended claims and illustrated in the accompanying drawings which form a part of this specification and in which—

Fig. 1 is a view of my ironing machine in side elevation.

Fig. 2 is a similar view to Fig. 1 showing the opposite side or end of the machine.

Fig. 3 is a view of the machine in front elevation.

Like reference characters denote corresponding parts throughout the several views.

My machine comprises a frame composed of the side members 1, 2 connected by the rods 3, the frame being disposed upon rollers 4. Upon the frame I provide the castings 5 that support the stationary shoe 6 which is of arcuate formation and is provided with the usual gas burner 7 whereby it is heated. A casting 8 bolted fast to the shoe operatively carries the drive shaft 9 whereon a pulley 10 is made fast, said pulley receiving power from a belt and motor (not shown) which motor may be supported upon a platform 11 carried by the frame of the machine and bolted to two of the connecting rods 3. The

said shaft 9 is formed with the worm 12 in mesh with the small gear 13 fast upon a transmission shaft 14 journaled in bearings 15 secured to the shoe 6, a large gear 16 also fast upon the shaft 14 being adapted for releasable operative engagement with the large gear 17 which is fast upon the roll shaft 18 that carries and rotates the padded roll 19 adapted to cooperate with the shoe 6 to iron the work.

The said roll shaft 18 is journaled in bearings 20 arranged upon sectional rock bars, one rock bar being disposed at each side of the frame and each rock bar comprising the sections 21, 22, the adjacent ends of the sections of each rock bar being formed with the lips 23, the adjacent lips being connected by a bolt 25 provided with the adjusting nut 26, and encircled by the tension spring 24. A threaded guide pin 27 also connects each pair of adjacent lips 23, said pin being threaded into engagement with one lip and extending loosely through a perforation in the adjacent lip. The rock bar sections 21 are formed with the extensions 28 which project beyond the roll 19 in front of the machine and support the work table 29 upon which the work is placed just previous to the ironing operation. The rock bar sections 22 are fulcrumed upon stub shafts 30, carried by the frame, between collars 31, 32 which are secured by set screws 33 to said shafts 30 and said sections 22 are connected by pins 34 to the longitudinally slotted portions 35 of the rockers 36 which are fulcrumed upon pins 37 carried by the frame, the rockers 36 at opposite sides of the frame being connected by the treadle 38 which treadle, at its longitudinal central portion, carries the twin angular castings 39 which are connected by the bolt 40 and pivotally arranged upon said bolt 40 between the castings 39 is the foot lever 41 which is formed with one upturned end for engagement with the longitudinally slotted link 42 fulcrumed upon a bolt 43 that connects the upstanding lugs 44 fast upon the connecting rod 3. Said link 42 is formed with the elongated slot 45 and with serrations 46 formed in its slotted portion, the slotted end of said link being disposed between the castings 39 and receiving the dog 47 fast upon the pivot 48 connecting said castings and extending through the said link-slot 45, said dog 47 being adapt-

ed for engagement with the serrations 46 in said link. The foot lever 41 aforesaid is engaged by an expansion spring 49 carried by the treadle 38. A foot rest 47^a serves to support the operator's foot in position to operate the foot lever 41.

The frame is provided with lugs 50 in alignment with similar lugs 51 formed upon the rock bar sections 21, said lugs 51 being formed with the elongated slots 52 and through said lugs 50, 51 (through the slots 52 of the latter) the screws 53 extend, tension springs 54 encircling said screw rods and abutting the said lugs 50, 51. A hand wheel 55 is arranged upon each screw rod for adjusting the same. The purpose of the springs 54 is to yieldingly keep the roll 19 and shoe 6 disengaged, likewise the gears 17, 16. Below the top of the frame and extending transversely of the same is the receiving table 56 adapted to receive the work after it has been ironed. Secured to the front of the frame and at each side of the same is a hinge 57 which carries a drying rack 58 secured thereto by set screws 59. With the leaves of the hinges extended the racks 58 extend outwardly from the frame as shown in Figs. 1 and 2. With the swinging leaves of the hinges turned the racks 58 are folded in toward the frame and out of the way as shown in Fig. 3.

The operation follows: The pulley 10 is running continuously and is driving the gear 16. Normally the springs 54 keep the gears 16, 17 disengaged. The work to be ironed is preferably placed upon the table 29 and it is fed, by the operator, upon the roll 19. To move the roll into engagement with the shoe 6 the operator depresses the foot rest 47^a. The downward movement of the same will move the treadle 38 and the outward ends of the rockers 36 downward. The castings 39 will be moved outwardly and downwardly with the treadle thus moving the dog 47 toward the serrations in the link 42. Before dog 47 actually encounters the serrations 46 the roll and shoe will be moved into operative position so that a garment fed between them will be ironed. If the foot rest is released the springs 54 will instantly separate the roll and shoe again. If the foot rest is depressed until the dog 47 engages with the serrations 46, however, the mechanism will be locked in operative position even though the operator should remove his foot entirely from the machine. To disengage the dog and serrations the operator depresses the free end of the foot pedal 41 thus raising the link 42 and the springs 54 will again move the roll and shoe out of engagement. The garments fall from the ironing members upon the receiving table 56 from which they may be manually removed and hung, if desired, upon the drying racks 58. By means of the hand wheels 55 the tension upon

springs 54 is regulated. The springs 24 connecting the rock bar sections will permit an adjustment of one end of the roll 19 automatically in the event that a garment of uneven thickness is being ironed. Should the roll and shoe not be exactly in alignment an automatic working adjustment of the roll to the shoe is likewise had through the action of these springs.

What is claimed is:—

1. In an ironing machine, in combination, a frame, a stationary shoe carried by said frame, sectional rock bars carried by said frame, flexible connections between the sections of said rock bars, a roll carried by said rock bars for engagement with said shoe, driving means for said roll when in engagement with said shoe, means connecting said frame and rock bars for yieldingly retaining said roll in disengaged relation with said shoe, and foot controlled means for actuating said rock bars. 75
2. In an ironing machine, in combination, a frame, a stationary shoe carried by said frame, rock bars carried by said frame, a roll pivotally carried by said rock bars for engagement with said shoe, driving means for said roll when in engagement with said shoe, spring means connecting said frame and rock bars for yieldingly retaining said roll in disengaged relation with said shoe, and foot controlled means for actuating said rock bars, said means including longitudinally slotted rockers fulcrumed to the frame and pins directly connecting the slotted portions of said rockers and said rock bars. 90
3. In an ironing machine, in combination, a frame, a stationary shoe carried by said frame, sectional rock bars carried by said frame, a work table carried by said rock bars, adjustable connections between the sections of said rock bars, said connections including expansion springs abutting said bar sections, a roll carried by said rock bars for engagement with said shoe, driving means for said roll when in engagement with said shoe, adjustable means connecting said frame and rock bars for yieldingly retaining the same in a predetermined position with the said roll and shoe disengaged, and foot controlled means for actuating said rock bars. 105
4. In an ironing machine, in combination, a frame, a stationary shoe carried by said frame, rock bars fulcrumed to said frame, a roll pivotally carried by said rock bars for yielding engagement with said shoe, driving means for said roll when in engaged relation with said shoe, foot controlled means for actuating said rock bars, said means including longitudinally slotted rockers fulcrumed to the frame and pins directly connecting the slotted portions of said rockers and said rock bars, and releasable locking means for said foot controlled means in one position of the same. 120

5. In an ironing machine, in combination, a stationary ironing member carried by said frame, rock bars fulcrumed to said frame, a movable ironing member carried by said rock bars for yielding engagement with said stationary ironing member, driving means for said movable ironing member, rockers fulcrumed to said frame, connections between said rockers and said rock bars, a treadle carried by said rockers, a longitudinally slotted and serrated link pivotally carried by said frame, spaced castings carried by said treadle, a dog carried by said castings for engagement with the slotted and serrated portions of said link, a foot pedal fulcrumed in said castings for operative engagement with said link, a spring yieldingly retaining said foot pedal inoperative, and a foot rest carried by said castings.
6. In an ironing machine, the combination of a frame comprising end standards, a substantially upright ironing shoe on said frame, pivot means on said end standards, substantially vertical rock bars mounted on said pivot means, each of said rock bars comprising a pair of sections yieldably connected together, an ironing roll having bearing support on the upper ends of said rock bars, means for driving said ironing roll, treadle means for swinging said rock bars and horizontally oscillating said ironing roll, the yielding connections between the sections of said rock bars being arranged to permit a substantially vertical adjusting motion of said ironing roll relative to said ironing shoe.
7. In an ironing machine, the combination of opposite upright end frames, a lever fulcrumed to swing in a plane parallel to said end frames and having one arm projecting upward and the other arm extending downward longitudinally of the end frames to swing back and forth horizontally between the front and back of said end frames, an ironing member secured to the upper arm of the lever, a treadle fulcrumed to said end frames, and means for transmitting up and down movement of said treadle intermediate the front and back of the end frames into horizontally back and

forth movement of the lower arm of the lever to swing the same.

8. In an ironing machine, the combination of opposite upright end frames, a lever fulcrumed to swing in a plane parallel to said end frames and having one arm projecting upward and the other arm extending downward longitudinally of the end frames to swing back and forth horizontally between the front and back of said end frames, an ironing member secured to the upper arm of the lever, a treadle, a crank arm having a sliding connection with the lower arm of the lever, and means connecting said treadle to said crank arm to rock the same.

9. In an ironing machine, the combination of a frame, an ironing shoe thereon, a pair of levers pivoted intermediate their lengths at opposite ends of said frame, a presser roll journaled between the corresponding ends of said levers, a rock shaft having crank arms to directly engage the other ends of the respective levers, means for rotating said rock shaft, and means for rotating said presser roll.

10. In an ironing machine, the combination of a supporting frame, a stationary ironing member and a movable ironing member, a lever structure supporting said movable element to be moved toward and away from said stationary element, a main treadle structure pivoted on said frame and connected with said lever mechanism, a pawl on said main treadle structure, a rack bar pivoted on said frame and engaging with said pawl, the teeth of said rack bar engaging with said pawl when said main treadle structure is depressed whereby to lock said treadle structure in down position and said movable element in engagement with the stationary element, and an auxiliary treadle supported on said main treadle structure and adapted when operated to raise said rack bar from engagement with said pawl whereby said main treadle structure will be released.

In testimony that I claim the foregoing as my own I have hereto affixed my signature.

AXEL R. GUSTAFSON.
